UNITED STATES PATENT OFFICE.

GEORGE R. LONG, OF WATERBURY, CONNECTICUT, ASSIGNOR TO SCOVILL MANUFACTURING COMPANY, OF WATERBURY, CONNECTICUT, A CORPORATION OF CONNECTICUT.

PUSH-BUTTON FAUCET.

987,633.

Specification of Letters Patent. Patented Mar. 21, 1911.

Application filed August 22, 1910. Serial No. 578,424.

To all whom it may concern:

Be it known that I, GEORGE R. LONG, a citizen of the United States, residing at Waterbury, in the county of New Haven and State of Connecticut, have invented a certain new and useful Improvement in Push-Button Faucets, of which the following is a full, clear, and exact description.

This invention is in the nature of an improvement upon the invention forming the subject of Letters Patent No. 953,342, dated March 29, 1910. As in the case of the patented invention, so here, the faucet is primarily designed for use in connection with the class of water-coolers in which the water vessel is surrounded by an ice-containing vessel, and the faucet is run through the outer vessel into the inner vessel and fastened water-tight to both vessels, so as to dispense the water from the inner vessel. Nevertheless, the utility and adaptability of the invention are not limited to this one class of articles.

The invention consists first in the means for connecting the push-button to the valve-stem, so as to provide for the ready assembling and dismembering of the parts, and, second, in the construction and arrangement of the adjacent parts, all as I will proceed now more particularly to set forth and claim.

In the accompanying drawing illustrating the invention, in the several figures of which like parts are similarly designated, Figure 1 is a vertical section of part of a water-cooler of the class referred to, with the faucet attached and shown in elevation. Fig. 2 is a longitudinal section on a larger scale. Fig. 3 is a sectional detail of the fastening. Fig. 4 is a perspective view of the fastening clip. Fig. 5 is a perspective view of the valve stem. Fig. 6 is a plan view of the fastening clip.

1 may represent the inner or water-containing vessel of a water cooler of the class described, and 2 may represent the outer or ice-containing vessel. These vessels may be spaced apart in any suitable way, and are perforated to receive the coupling 3 by means of which and suitable washers 4 and 5, and packing 6 and 7 and other accessories, the faucet is secured to them in a fluid-tight manner. This coupling 3 engages a nut 8 which in turn screws into the inner end 9 of the body 10 of the faucet. The end

9 and body 10 may be separate parts, as shown, or unitary, as desired. Within the end 9 is a renewable valve seat 11 held in place by a nut 12. The valve 13 has a stem 14 extending outwardly through the body, and said valve is held to its seat and normally seated by a spring 15 encircling the outer end of the stem and held between a shell 16 rigid in the body and a fastening clip 17 on the end of the stem. The push-button 18 is applied to the device over the clip 17, and while of reduced external diameter, it is preferably bell-mouthed at 19 to fit more or less snugly within the body 10. This clip is a shell-like split-spring, as in the patent referred to, but one of the edges of its split rim has an out-turned tongue 20 which is adapted to engage a slot 21 in the rim of the push-button, so as to hold said push-button in place on the valve stem and in the body of the faucet. By depressing the tongue 20, under the resilience of the clip, said clip may be displaced from the push-button and the parts thus disconnected, but the important point is the facility with which the push-button may be applied to the valve and faucet body by means of the tongue and slot connection. It will be understood that by pressure exerted longitudinally upon the push-button, the valve may be unseated for the out-flow of the fluid from the inner vessel. The exit nozzle 22 provides the escape for the outflowing fluid, and this nozzle may be applied to or made with the body.

The shell 16 may be inserted and held frictionally in the body under limitation of the bead 23 made in the body, and adjacent to this bead the body may be provided with the external collar 24, to serve as a finger-hold in operating the faucet. The hole 25 in the shell for the passage of the valve-stem may be made fluid-tight by a soft washer 26 of leather or other material, and there may be provided a protecting washer 100 27 of metal to take the wear of the spring 15.

The spring clip is shell-like, divided cross-wise at 28, with square edges 29 to engage parallel grooves 30 in the valve-stem 14, and held in such engagement by its resilience 105 supplemented by the compression exerted by confinement within the push-button, as in the patent referred to.

Unlike the body in the patent, the body herein is open at both ends, and thus an 110

economy in construction is effected. In order to express this difference, the body is herein referred to as open-ended.

Between the nut 8 and the inner end 9 of the body, there may be interposed the gasket 31.

Variations in the constructions are deemed within the spirit and scope of the invention, especially as the main feature of the invention is an externally accessible medium for connecting the push-button with the valve and the body of the faucet.

What I claim is:

1. A push-faucet having a body, a valve provided with a stem, a push-button, a spring acting upon the push-button, and means applied to said stem and carried by it and engaging the push-button and serving to retain the push-button and spring in operative relation with the body and stem and allowing the removal of the push-button from such operative relation, said means externally accessible for permitting such removal.

2. A push-faucet, having an open-ended body, a valve and its stem arranged therein, a spring applied to the stem to seat said valve, a push-button arranged in the end of the body and having a slot in its side, and a clip applied to the valve-stem over the spring and having a tongue in detachable engagement with the slot in the push button.

3. A push-faucet having a body, a valve provided with a stem, a push-button, and means for retaining the push-button in operative relation with the body and stem and allowing the removal of the push-button from such operative relation, said means including a spring-pressed tongue engaging a slot in the push-button and externally accessible for permitting such removal.

4. A push-faucet having a body, a valve provided with a stem, a push-button fitted in the body, and means for retaining the push-button fitted in the body, and means 45 for retaining the push-button in operative relation with the body and in interlocking engagement with the valve-stem and allowing the removal of the push-button from such relation and engagement, said means externally accessible 50 for permitting such removal.

5. A push-faucet, having an open-ended body, a valve and valve-stem therein, a spring to hold said valve to its seat, a push-button slidably fitted in the outer end of said body, 55 and a spring clip connected to the valve-stem and having frictional and positive engagement with the push-button.

6. A push-faucet, having an open-ended body, a valve and valve-stem therein, a spring to hold said valve to its seat, a shell arranged in the body to support the spring, a push-button slidably fitted in the outer end of said body, and a spring clip connected 60 to the valve-stem and having frictional and positive engagement with the push-button.

7. A push-faucet, having an open-ended body, a valve and valve-stem therein, a spring to hold said valve to its seat, a shell arranged in the body to support the spring, 70 a push-button slidably fitted in the outer end of said body, and a spring clip having frictional and positive engagement with the push-button and positive engagement with the valve-stem to hold the push-button and 75 spring in position.

In testimony whereof I have hereunto set my hand this 19th day of August A. D. 1910.

GEORGE R. LONG.

Copies of this patent may be obtained for five cents each, by addressing the "Commissioner of Patents, Washington, D. C."

It is hereby certified that in Letters Patent No. 987,633, granted March 21, 1911, upon the application of George R. Long, of Waterbury, Connecticut, for an improvement in "Push-Button Faucets," an error appears in the printed specification requiring correction as follows: Page 2, line 45, the words "push-button fitted in the body, and means" should be stricken out; and that the said Letters Patent should be read with this correction therein that the same may conform to the record of the case in the Patent Office.

Signed and sealed this 18th day of April, A. D., 1911.

[SEAL.]

C. C. BILLINGS,
Acting Commissioner of Patents.
